UNITED STATES PATENT OFFICE.

WILLIAM H. SAUVAGE, OF FLUSHING, NEW YORK.

HAND BRAKE.

1,420,151.

Specification of Letters Patent. Patented June 20, 1922.

Application filed August 7, 1919. Serial No. 315,909.

To all whom it may concern:

Be it known that I, WILLIAM H. SAUVAGE, a citizen of the United States, residing at Flushing, Long Island, in the county of 5 Queens and State of New York, have invented certain new and useful Improvements in Hand Brakes, of which the following is a specification.

This invention relates to hand brakes and 10 more particularly to high power hand brakes particularly adapted for use on railway vehicles of all kinds.

One of the objects of the present invention is to provide a simple and practical 15 high power hand brake having relatively few parts and which will be of strong and durable construction. A further object is to provide a reliable and efficient hand brake of the above character adapted to prevent 20 over-load strain being exerted upon the brake rigging. A further object is to provide a brake of the above character which may be applied to the brake rigging now in general use without material alterations. 25 A further object is to provide a hand brake for railway vehicles which will allow the brakes to be easily and quickly taken up with a maximum amount of power, and which will have its working parts so completely housed and protected as to be unaffected by atmospheric conditions.

A further object is to provide a hand brake free from ratchet or other unreliable mechanism that so often cause accidents.

30 Other objects will be in part obvious from the annexed drawings and in part indicated in connection therewith by the following analysis of this invention.

This invention accordingly consists in the 40 features of construction, combination of parts and in the unique relations of the members and in the relative proportioning and disposition thereof, all as more completely outlined herein.

To enable others skilled in the art so fully 45 to comprehend the underlying features thereof that they may embody the same by the numerous modifications in structure and relation contemplated by this invention, 50 drawings depicting a preferred form have been annexed as a part of this disclosure, and

in such drawings, like characters of reference denote corresponding parts throughout all the views, in which—

Fig. 1 is a front elevational view, partly 55 in section, showing the complete mechanism;

Fig. 2 is a horizontal plan view partly in section.

Referring now to the drawings in detail 60 5 denotes a casing of any desired type, adapted to be secured to the front end of the car, for example, by means of the fastening devices passing through perforated lugs 6. This casing is provided with a removable cover, or plates as necessary, whereby the parts may be conveniently assembled. Within the casing is mounted a shaft 7 provided with hand operating means such as a wheel 8 provided with a handle 10. This 70 shaft is mounted in suitable bearings in the upper part of the casing and has throughout the major portion of its length threads 11 adapted to mesh with a worm pinion 12 carried by shaft 13 mounted in the casing. 75 Also mounted upon this shaft 13 is a spiral winding drum 14 upon which a cable or chain 15 is adapted to be wound. As herein shown, this chain passes through a sheave 16 and has its opposite end connected with 80 an eye 17, the sheave 16 being connected to the load chain or pull rod as shown. If a low power is desired the chain 15 may be directly connected with the foundation 85

brake rigging. In order to take up the end thrust exerted upon the worm 11 there is provided a thrust ball bearing 20 as shown in Fig. 1, one part of which coacts with the shaft 7 and the other is held by a washer 22 yieldingly held 90 in place by means of a spring 23 seated in chamber 24. The washer preferably has a lug 25 adapted to slide in a groove or slot 26 to prevent turning. This sliding movement takes place when excess load occurs, or 95 in other words is adapted to move when a lug 27 carried by the shaft 7 laterally engages with a cam lug 28 on the casing 5, thereby positively preventing a further turning of the hand wheel 8. The cam permits 100 unwinding at any time. This prevents excess power being transmitted to the founda-

tion brake rigging which might break some of the connecting links.

The operation of this device is substantially as follows: Assuming the parts to be 5 in the position shown in Fig. 1, a rotation of the hand wheel will cause the chain 15 to wind up on the spiral drum with a constantly increasing power. If this power exceeds a predetermined amount however, as 10 provided for by the spring 23, which if desired may be adjusted to any degree of tension, then the brake pressure will cause the shaft 7 to move relatively towards the left, whereby the stops 27 and 28 come into engagement, thus preventing a further turning 15 of the hand wheel 8.

From the above it will be seen that the invention provides a simple hand brake having relatively few parts adapted to give the 20 maximum high power quick take up and release, and one which will be thoroughly reliable and efficient in use and operation.

I realize that considerable variation is possible in the details of construction and 25 arrangement of parts without departing from the spirit of my invention, and I therefore do not intend to limit myself to the specific form shown and described.

I claim:

30 1. In a hand brake, in combination, a support, a shaft mounted therein, a thread on the shaft, a pinion meshing with the shaft, a spiral drum adapted to be actuated by the pinion, and means adapted to prevent overloading by locking said shaft against further rotation.

2. In a hand brake, in combination, a shaft, a spiral winding drum geared thereto, and means adapted to prevent overload on said 40 drum by locking said shaft against further rotation.

3. In a hand brake, in combination, a shaft, a spiral winding drum geared thereto, and means adapted to prevent overload, said 45 means comprising a stop, and means permitting a longitudinal movement of the shaft on overload to carry the stop to operative position.

4. In a hand brake, in combination, a shaft, 50 a worm and pinion associated therewith, a spiral drum adapted to be rotated thereby and upon which a brake chain is adapted to be wound and a lock for said shaft yieldingly held out of operation until the drum is subjected to overload.

5. In a hand brake, in combination, a longitudinally movable shaft, a worm and pinion associated therewith, a spiral drum adapted to be rotated thereby and upon 60 which a brake chain is adapted to be wound, a yielding thrust bearing for said shaft and a lock for preventing further movement of said shaft when said thrust bearing yields.

6. In a hand brake, in combination, a shaft, 65 a worm and pinion associated therewith, a

spiral drum adapted to be rotated thereby and upon which a brake chain is adapted to be wound, a thrust bearing for said shaft, means adapted to permit a longitudinal movement of said shaft upon overload and 70 means preventing application of the brakes after overload occurs.

7. In a hand brake, in combination, a shaft, a worm and pinion associated therewith, a spiral drum adapted to be rotated thereby 75 and upon which a brake chain is adapted to be wound, a thrust bearing for said shaft, means adapted to permit a longitudinal movement of said shaft upon overload, and means associated with said shaft for locking 80 the same against rotation when such predetermined longitudinal movement takes place.

8. In a hand brake, in combination, a casing, a shaft having a thread thereon, a pinion meshing therewith, a member adapted to be turned by said pinion to apply the brakes, a thrust bearing and a yielding support for said thrust bearing having means to prevent rotary movement of said shaft.

9. In a hand brake, in combination, a casing, a shaft having a thread thereon, a pinion meshing therewith, a drum adapted to be turned by said pinion, a thrust bearing, and means adapted to lock said shaft against rotation when said thrust bearing yields on 95 overload.

10. In a hand brake, in combination, a casing, a shaft mounted therein, a drum upon which a brake chain is adapted to be wound, means for transmitting motion from the shaft to the drum, and a lock for said shaft operative on overload on said drum.

11. In a hand brake, in combination, a casing, a spiral drum upon which a brake chain is adapted to be wound, means for transmitting motion from the shaft to the drum, and a lock for said shaft when overload takes 105 place, said locking means comprising a lug on said shaft and a lock on the casing adapted to be engaged thereby.

12. In a hand brake, in combination, a casing, a worm shaft therein, a spiral drum upon which a brake chain is adapted to be wound, means for transmitting motion from the shaft to the drum, and means yieldingly 115 supporting one end of said shaft against overloading, comprising a spring, and a thrust bearing interposed between the spring and the shaft, also means for locking said shaft against further rotation when said thrust bearing yields.

13. In a hand brake, in combination, a casing, a moveable threaded shaft mounted therein, a yielding thrust bearing and intervening ball bearing adapted to co-act therewith, a pinion operatively associated with said threaded shaft, a spiral drum adapted to be rotated by the associated shaft and pinion, automatic stop means associated with said shaft and operatively associated with 130

said yielding thrust bearing, and a brake chain adapted to be wound on said spiral drum.

14. In a hand brake, in combination, a casing, a movable threaded shaft mounted therein, a pinion in mesh therewith, an associated spiral member, a chain adapted to be wound thereon, a ball thrust bearing, a yielding support therefor, said casing having a

guide slot for said bearing, said thrust bearing being intermediately positioned between the yielding support and the threaded shaft, means adapted to lock said shaft against further rotation in braking direction yet positioned to permit immediate reverse rotation 15 of the shaft.

In testimony whereof I affix my signature.
WILLIAM H. SAUVAGE.
